Attorney.

UNITED STATES PATENT OFFICE.

FREDERICK DRIFFILL, OF STERLING, ASSIGNOR TO THE EUREKA COMPANY,
OF ROCK FALLS, ILLINOIS.

ROAD-CART SPRING.

SPECIFICATION forming part of Letters Patent No. 399,852, dated March 19, 1889.

Application filed September 12, 1888. Serial No. 285,250. (No model.)

To all whom it may concern:

Be it known that I, FREDERICK DRIFFILL, a citizen of the United States, residing at Sterling, in the county of Whiteside and State of Illinois, have invented certain new and useful Improvements in Road-Cart Springs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention has reference to certain improvements in road-carts, and pertains more especially to the mode of suspending the body of the vehicle to the running-gears thereof.

The special object of my invention is to support the weight of the body of the vehicle and its occupant in a peculiar mode to the thills, or some suitable part connected thereto, adjustably upon coiled springs, and to so use the latter in such relation to other parts as to 25 avoid the rattling which has heretofore accompanied and which is an objectionable feature in such use.

As the mode of suspension at each side of the vehicle is the same as that at the other side, I do not deem it necessary to describe more than one of said modes of suspension.

In the drawings, Figure 1 is a perspective of a part of a road-cart containing my invention. Fig. 2 is a detail of the spring and its adjunctive parts. Fig. 3 is a plan of the upper cap or cross plate of the frame which incloses the spring.

A A are the usual carrying-wheels.

B is the axle, and C C the thills attached at 40 their rear ends in any suitable mode to said axle.

D is the frame, within which the supporting-springs are seated. The frame D consists of the two downwardly-divergent rods E E, 45 bent inwardly, respectively, at their lower ends to form centrally the depending loop F, and suitably fastened at their upper ends in the extremities of the cross-plate G. In the cross-plate G there is centrally formed an opening, H, through which there is vertically passed

a core or spring-rod, J, which extends downward through the coiled spring K. The upper end of the rod J projects above the plate G, and is there formed into loop J', by means of which the frame D is pivotally attached in any suitable manner to the thills C or some part of the running-gears connected therewith. On the lower and depending end of the rod J is adjustably seated a circular plate, L, upon which the lower end of the spring K is seated. 55 The upper end of the spring K abuts against the lower surface of the cross-plate G, and in the use of the spring the latter is compressed and released between said plate L and plate G. On the upper face of the plate L is formed a 60 circular boss, M, which, with the plate L, has a threaded central opening, M', through which the rod J passes, and by means of conforming threads formed on the contiguous portion of the rod J the plate L can be adjusted vertically to form a proper seat for the lower end of the spring K and regulate the compression of the latter. On the under side of the plate G is centrally formed the downwardly-extending annular flange N, the opening O therein 65 conforming to the central opening in the plate G and constituting a downward prolongation of said latter opening, and said flange N, being projected within the adjacent end of the spring K, serves to hold the latter in proper 70 position. The circumference of the boss M and flange N is substantially the same as the end openings in the spring K. Therefore the contiguous portions of said spring are coiled 75 around and rest upon the periphery of said boss and flange, respectively. The loop J is attached pivotally, as aforesaid, to the running-gears of the vehicle, and the body of the latter is pivotally attached in any suitable manner to the loop F at the lower end of said 80 frame, or the said frame may be optionally used in an inverted position.

The frame D can be attached to any suitable portion of the body of the vehicle at each side of the latter, respectively, at some suitable point in the rear of the forward end of said body, said forward end being pivotally connected to the thills C, or some part of the running-gears connected therewith, in the usual manner.

To avoid the rattle or noise aforesaid usually attendant upon the use of the coiled springs under similar circumstances, and to render the reciprocal movement of the rod J in the opening H noiseless, and at the same time in a direct line, I make the opening H in the plate G and the opening O in flange N sufficiently larger than the rod J to permit the seating in said opening of the cushion P. The exterior conformation of the cushion P is such as to tightly fill both of the openings H and O, and said cushion is firmly seated in said openings by compression thereof, wedging, or any other suitable mode. A vertical opening, 15 R, is formed centrally in the cushion P for the passage of the rod J, and is of such size as to permit said rod to reciprocate in said cushion without unnecessary friction or binding. The cushion P can be made of wood, 20 rubber, cork, or any other non-resonant material.

By the use of the cushion P the rod J is held centrally in a direct line with the frame D, is permitted to reciprocate freely, and the usual 25 wear and noise consequent upon the striking of said rod against the walls of the plate G or its analogous part are avoided. The prolongation of the opening H afforded by the annular flange N provides a more secure and greater 30 depth of seat for the cushion P.

The rods E E are made downwardly divergent to prevent the lower portion of the spring

K in its lateral vibrations from striking against said rods.

What I claim as my invention, and desire 35 to secure by Letters Patent of the United States, is—

1. In combination with the body and running-gears of a road-cart, the rods E E, relatively downwardly divergent, the loop F, the 40 cross-plate G, provided with the enlarged opening H and flange N, the rod J, provided with loop J' and lower threaded exterior, the plate L, provided with boss M and threaded opening M', and the cushion P, provided with the 45 opening R, substantially as shown, and for the purpose described.

2. In combination with the body and axle of a road-cart, the thills C, rods J, provided with the loop J', adapted to be attached to 50 said thills, the rods E E, relatively downwardly divergent and provided with the loop F, adapted to be attached to the body of the vehicle, cross-plate G, provided with the enlarged opening H and flange N, the plate L, 55 provided with boss M, and the cushion P, provided with the opening R, substantially as shown, and for the purpose described.

In testimony whereof I affix my signature in presence of two witnesses.

FREDERICK DRIFILL.
